Attorney's

UNITED STATES PATENT OFFICE

DEZSÖ HORNYÁK, OF CLEVELAND, OHIO

LIFE SAVING SUIT

Application filed October 1, 1932. Serial No. 635,832.

This invention relates to life saving suits particularly of the type adapted to enclose the entire body exclusive of the head.

The primary object of this invention is to provide a suit of the above mentioned character having a water-tight neck connection to prevent water from leaking through to the interior of the suit around the neck of the wearer.

10 A further object of this invention is to provide a life saving suit of the above mentioned character which may be formed of rubber or rubberized fabric and which may be provided with a sliding closure extending from the neck of the suit to substantially the waist line.

20 A still further object of this invention is to provide a life saving suit having an adjustable neck portion or collar which may be adjusted by manipulating a pair of oppositely disposed screw threaded shafts to move semi-circular yokes into engagement with the user's neck.

25 A still further object of this invention is to provide a neck portion or collar for the life saving suit formed of semi-circular sections hinged together and locked at the free ends by means of a snap fastener whereby the suit may be readily applied or removed without requiring considerable time on the operator's part.

30 A still further object of this invention is to provide a life saving suit with a neck engaging portion in which each of the semi-circular members are formed hollow in order to provide air spaces which form buoyant members whereby the user will always assume an upright position in the water regardless 40 of the manner or position assumed while entering the water.

45 Other objects and advantages of the invention will become apparent during the course of the following description, forming a part of the specification and in which,

Figure 1 is a front elevational view of a life saving suit embodying the invention;

50 Figure 2 is a top elevational view of the collar or neck engaging portion illustrating the construction thereof and illustrating the

semi-circular hinged sections along with the adjustable neck engaging yoke members;

55 Figure 3 is a rear elevational view of the semi-circular neck engaging members showing the manner in which they are hinged together in the back showing the yoke adjusting screws carried by each semi-circular section;

60 Figure 4 is a front elevational view of the semi-circular neck engaging members illustrating the closure fastener or hasp for securing the hinged sections together;

65 Figure 5 is a transverse cross-sectional view taken through the neck engaging collar illustrating the air chambers formed in the semi-circular members and also showing the manner in which the semi-circular yokes are adjustably mounted and operated by the screw threaded shaft;

70 Figure 6 is a top elevational view of one of the semi-circular members showing the cover of the air chamber removed;

75 Figure 7 is an interior side elevational view of one of the neck engaging semi-circular members illustrating the channel-way in which the semi-circular yokes are positioned; and

80 Figure 8 is a top elevational view of one of the semi-circular yoke members illustrating the manner in which the screw threaded adjusting rod is attached thereto.

85 In the drawings, wherein for the purpose of illustrating the invention and wherein like reference characters will be employed to designate like parts throughout the same, the reference character 10 will generally be employed to designate a life saving suit which may be preferably formed of rubber or rubberized fabric including a trunk or pants portion 11 suspended from a waist band 12 to which is connected a shirt portion 13 having sleeves 14 and a neck portion 15. The sleeves 14 are provided at the open ends with wrist portions 16 and rubber gloves 17 while the shirt or waist portion 13 is provided with a sliding closure 18 which extends from the neck portion 15 to the waist band 12. The pants portion 11 are bifurcated and are provided with rubber shoes which may be cemented or fastened to the pants portion 11. 90 95 100

in any well known manner after the same fashion as the gloves 17.

The neck portion 15 is provided with a neck engaging yoke 20 which is more clearly

- 5 illustrated in Figures 2 to 8 inclusive and comprises semi-circular portions 21 and 22 hinged together as at 23 by means of a suitable hinge fastened to the semi-circular neck engaging portion by rivets or the like 24.
- 10 The hinge is provided with a pintle 25 which extends through the leaves 26. It is intended to cement the neck engaging portion 15 to the semi-circular sections 21 and 22 and after cementing the same in place, it is intended to
- 15 vulcanize the same to prevent leakage of water.

The free ends of the semi-circular members 21 and 22 are adapted to be connected together by means of a hasp which includes a 20 leaf 27 secured in place by rivets or the like 28 to which is hinged a pivoted member 29 as at 30 having therein a slot 31 for receiving a loop member 32 secured to a plate 33 rigidly secured to one of the semi-circular members 25 as at 22. A swinging catch 34 is pivoted to the pivoted fastening member 29 as at 35 and is provided with a hooked end 36 adapted to be passed through the loop 32 whereby the two sections 21 and 22 may be securely held 30 together.

Each of the semi-circular members 21 and 22 is provided with circular cut-out portions 37 and 38 which describe an opening of sufficient size for the user of the life saving suit 35 to adequately receive his neck. As shown in Figure 6, the semi-circular members are each formed identically alike and each comprise a casting having arcuately curved outer walls 39 and arcuately curved inner walls 38 which 40 are substantially in concentric relation to each other and said inner and outer walls 38 and 39 extend upwardly from a bottom wall 40 while the ends are closed by end walls 41. Formed on the interior of the inner wall 38 45 is a pair of semi-circular rib members 42 which form a channel-way 43 for receiving adjustable yoke members which will be hereinafter fully described.

Each of the semi-circular members 21 and 50 22 as shown in Figures 6 and 7 is provided with bosses 45 arranged in staggered relation so that a cover 46 may be applied thereto and held in place by screws 47. Each of the covers 46 are of substantially the same 55 configuration as the semi-circular members 21 and 22 and are formed identical in shape and construction. Interposed between the cover 46 and the semi-circular casing comprising the side wall 38, 39 and bottom wall 60 40 is a semi-circular packing member 48 which is adapted to prevent leakage of water into the chamber 49 adapted to be employed by an air drum by reason of the fact that the air sealed therein forms a buoy for the life 65 saving suit 10 which will assist the user there-

of to stay upon the surface of the water when using the garment.

Each of the cover plates 46 is provided with leaf members 50 secured in place by rivets or the like 51 and adapted to be connected together by removable pintles 52 as clearly shown in Figures 2, 3 and 4, whereby the structure will be braced and prevent separation of the sections 22 and will prevent the resulting tearing or ripping of the semi-circular sections from the waist or neck portion of the garment.

Slidably mounted in each of the grooves 43 of the semi-circular members are yoke members 55 which are arcuately curved so as to be snugly received within the grooves 43, and said yoke members 55 are preferably formed of a soft material capable of engaging the neck of the user for preventing water from entering the interior of the suit 10 through the neck opening 15. Centrally journaled relative to each of the semi-circular yoke members 55 is a screw threaded rod 56 having a thumb engaging portion 57 and said rods 56 are screw threaded in the bottom 90 wall 40 as clearly shown in Figure 5 and designated by the reference character 58. By operating the thumb portion 57 the arcuately curved yoke 55 may be moved in the groove 43 toward or away from the user's 95 neck, thereby forming a complete seal against the inclusion of water.

It is to be understood that the invention forms a float by reason of the air chamber 49 as well as a neck engaging portion which is 100 adapted to seal the suit against the inclusion of water and that various changes may be made relative to the size, shape and construction of the device without departing from the spirit of the invention or the scope 105 of the sub-joined claims.

Having thus described the invention, what I claim is:—

1. A life saving garment of the character described, comprising a bifurcated trunk portion, a waist portion having sleeves and a neck portion, a sliding closure extending from the neck portion to the bottom of the waist portion, a pair of semi-circular hinged neck engaging members carried by the neck 110 portion, means for fastening the semi-circular members together, an air chamber incorporated in the semi-circular members and adjustable sealing members carried by the semi-circular members.

2. A life saving garment of the character described, comprising a neck portion, semi-circular hinged members carried by the neck portion, an air chamber incorporated in each of the semi-circular members, means 115 for fastening the semi-circular members together and adjustable sealing members carried by each of the semi-circular members adapted to engage the neck of the wearer and prevent the intrusion of water.

3. A life saving garment comprising a bifurcated union suit formed of a flexible water-proof material, sleeve and leg portions formed on the suit, a neck opening formed
5 in the upper portion of the suit, a sliding closure extending from the neck opening to the mid-section of the garment, a pair of hinged semi-circular hollow members secured to the neck portion so that the hinge will be in the
10 rear, a closure member for the front of the semi-circular members and sliding sealing members carried by each of the semi-circular members adapted to engage the neck of the wearer and prevent the intrusion of water.
- 15 4. A life saving garment of the character described, comprising a bifurcated suit having arm, leg and neck portions, a sliding closure extending from the neck portion to the mid-section of the suit, closure members for
20 the sleeve and leg portions of the suit, a pair of hinged semi-circular hollow members secured to the neck portion, a fastener for securing the free ends of the semi-circular members together, an interior annular groove
25 formed on each of the semi-circular members, arcuately curved sealing members slidably mounted in the groove, and means associated with each of the arcuately curved sealing members for adjusting the same relative to the semi-circular members.
- 30 5. A life saving garment of the character described, comprising a bifurcated suit having leg, arm and neck portions, closures for the leg and arm portions, a sliding closure
35 extending from the neck portion to the mid-section of the bifurcated suit, a pair of hinged semi-circular members having an interior air space secured to the neck portion of the garment, means carried by each of the semi-circular members for locking the same together, a semi-annular groove formed interiorly of each of the semi-circular members, a sliding neck engaging member received in each of the grooves, a screw threaded shaft having one
40 of its ends journaled in the sliding sealing member and the opposite ends provided with a thumb engaging portion whereby turning the thumb engaging portion will move the sealing members into engagement with the
45 neck of the user.

In testimony whereof I affix my signature.
DEZSÖ HORNYÁK.
